UNITED STATES PATENT OFFICE.

HIRAM W. BLAISDELL, OF LOS ANGELES, CALIFORNIA.

CONVEYING SYSTEM.

No. 830,045.

Specification of Letters Patent.

Patented Sept. 4, 1906.

Application filed February 1, 1904. Serial No. 191,610.

To all whom it may concern:

Be it known that I, HIRAM W. BLAISDELL, a citizen of the United States, residing at Los Angeles, in the county of Los Angeles 5 and State of California, have invented certain new and useful Improvements in Conveying Systems; and I do hereby declare the following to be a full, clear, and exact description of the invention, such as will enable 10 others skilled in the art to which it appertains to make and use the same.

This invention relates to conveyers, and particularly to systems of conveyers wherein more than one conveyer is employed; and 15 some of the objects of the invention are to provide a conveyer system which will be simple and cheap in construction as well as efficient in operation.

Another object of the invention is to provide a conveyer system wherein the main and auxiliary conveyers are so arranged as to effect great economy in space, while permitting of the location of the major portion of the main conveyer in a plane above the auxiliary conveyer, whereon it discharges. 25

A further object of the invention is to provide an auxiliary conveyer in a plane above the main portion of the main conveyer, said conveyers being so arranged in relation to 30 each other that the loaded lead of each conveyer is brought into closest proximity or relation to each other.

With these and other objects in view the invention consists, essentially, in the construction, combination, and arrangement of parts, substantially as more fully described 35 in the following specification and as illustrated in the accompanying drawings, forming part of this application, in which—

40 Figure 1 is an elevational view, partly broken away and partly in section, showing an application of the invention. Fig. 2 is an elevational view, partly broken away, taken at right angles to Fig. 1. Fig. 3 is a diagrammatic perspective view illustrating the operative relation of the main and auxiliary conveyers.

Similar characters of reference designate corresponding parts throughout the several 45 views.

Referring to the drawings, and particularly to the construction illustrated in Figs. 1 and 2 thereof, reference character 1 designates portions of the supporting posts or framing, whereon are secured beams or timbers 2, with track-rails 3 located thereon and

constructed to receive supporting-wheels or a traveling structure or bridge 5, whereon may be secured a platform or frame 6, carrying uprights 7, with which and the platform 6 are connected inclined members or a frame 8, supporting sets of curved rollers or troughing-idlers 9, substantially as shown.

Revolutely mounted or journaled upon the upright 7 is a discharge-roller or dump-pulley 10, below which is likewise mounted a guide-roller or bend-pulley 11, while on the end of the platform is preferably mounted a supporting-roller 12, and secured upon a framing or structure 13 is mounted an inverted trough 14, in which are mounted sets of straight pulleys or rollers 15, and above which are mounted sets of curved pulleys or troughing-idlers 16, over which sets of rollers travel a main endless conveyer or belt 17, which also 75 passes up over the sets of troughing-idlers 9 on the tripper-frame and over the dump-pulley 10 and a guide-roller 11 and supporting-roller 12 back to the sets of troughing-idlers 16, as will be readily understood by those 80 skilled in the art to which this invention appertains.

Brackets 18 are preferably mounted upon the ends of the traveling structure or bridge 5, and in said brackets are journaled shafts 85 19, carrying rollers or pulleys 20, over which passes the auxiliary or cross conveyer 21, the intermediate portion whereof is preferably supported by sets of curved or straight rollers 22 and 23, respectively, substantially as 90 shown in Fig. 1 of the drawings.

A motor or other driving device 24 may be mounted upon the traveling structure or bridge and may be provided with a usual band-pulley 25, belted to a band-wheel 26 on 95 one of the shafts 19, by means of which the auxiliary conveyer is driven, as will be readily understood.

By means of the construction described and shown the auxiliary cross-conveyer is 100 made to straddle or overlap the main conveyer, as clearly shown in the enlarged diagrammatic perspective view in Fig. 3 of the drawings, and by this means the upper or loaded lead of the main conveyer 17 and the 105 similar lead of the auxiliary or cross conveyer 21 are brought very close to each other, and the discharging of the material from the upper or loaded lead of the main conveyer 17 upon the loaded lead of the auxiliary conveyer is greatly facilitated; but this construction is particularly desirable and necessary to 110

economize space or room occupied by the two conveyers and the degrees of height of the main conveyer at the place of discharge, which has been demonstrated to be very essential in the construction and operation of such a conveyer system.

The operation of this invention will be readily understood from the foregoing description when taken in connection with the accompanying drawings and the following explanation thereof.

The material is placed upon the main conveyer in any suitable manner, and said conveyer may be provided with any desired driving means, and the conveyer is moved or progressed in the direction indicated by arrows in Figs. 2 and 3 of the drawings until it passes up over the sets of troughing-idlers 9 upon the inclined frame or timbers 8 to and over the dump-pulley 10, and a hood or casting 22^a may be provided at this point if found desirable in practice, and from the dump-pulley 10 the main conveyer 17 passes down under the bend-pulley 11 and between the leads of the auxiliary conveyer to and over the supporting-pulley 12 and back to the sets of troughing-idlers 16 on the frame or timbers 2 to and around an end or tail pulley (not shown) in the usual manner.

30 The material discharged by the main conveyer 17 when passing over the dump-pulley 10 is received by the upper curved lead of the auxiliary conveyer 21 and is conveyed thereby to the end of the traveling structure or bridge or to any other place of discharge, as will be readily understood.

It is not desired to limit or confine this invention to the specific construction, combination, and arrangement of parts herein shown and described, and the right is reserved to make all such changes in and modifications of the same as come within the spirit and scope of the invention.

I claim—

45 1. A conveying system provided with a main conveyer, an auxiliary conveyer at an angle thereto, the upper lead of the main conveyer being between the leads of the auxiliary conveyer and the lower lead of said main conveyer being below the lower leads of said auxiliary conveyer.

2. A conveying system provided with a

main conveyer, means for elevating a portion thereof, an auxiliary conveyer in a plane above the major portion of said main conveyer and straddling said main conveyer and means for operating the conveyers.

3. A conveying system provided with a main conveyer, a traveling device for elevating a portion thereof, an auxiliary conveyer 60 in a plane above the major portion of said main conveyer and straddling said main conveyer and means for operating said conveyers.

4. A conveying system provided with a 65 traveling structure, an elevating device thereon, a main conveyer passing over said device, an auxiliary conveyer in a plane above the major portion of said main conveyer and straddling said main conveyer and 70 means for operating said conveyers.

5. A conveying system provided with a main conveyer, a tripper thereon, an auxiliary conveyer straddling the upper lead of said main conveyer and means for operating 75 the parts.

6. A conveying system provided with a traveling structure, an elevating device, a main conveyer passing over said device, an auxiliary conveyer upon said structure straddling the upper lead of said main conveyer and means for operating said conveyers.

7. A conveying system provided with a main conveyer, means for imparting different elevations thereto, an auxiliary conveyer 85 straddling said main conveyer thereby bringing the carrying-leads of said conveyers adjacent and means for operating said conveyers.

8. A conveying system provided with a 90 main conveyer, a tripper thereon carried by a gauntlet, and an auxiliary conveyer on said gauntlet the leads of which straddle the upper lead of said main conveyer.

In testimony whereof I have signed my name to this specification, in the presence of two subscribing witnesses, at Los Angeles, county of Los Angeles, State of California, this 23d day of January, 1904.

HIRAM W. BLAISDELL.

Witnesses:

CHARLES S. ROGERS,
MIGNON FORD.
